(57) **CLAIM**

The ornamental design for a hat with an auxiliary strap as shown and described.

DESCRIPTION

The patent or application file contains at least one drawing executed in color. Copies of this patent or patent application publication with color drawing(s) will be provided by the Office upon request and payment of the necessary fee.

1. Hat with an auxiliary strap

1.1 : Perspective

1.2 : Front

1.3 : Back

1.4 : Top

1.5 : Bottom

1.6 : Left

1.7 : Right

The present design is a partial design, and the design registration is sought for all parts except the yellow portion in FIG. 1.1 to FIG. 1.7; the characteristic features of the design lie in the shape of the auxiliary strap attached to the hat.
